UNITED STATES PATENT OFFICE.

JOHN SWANZY HARLEY, OF WALTHAM ABBEY, ENGLAND.

PRODUCTION OF YARN, TWINE, CORD, AND THE LIKE BY SPINNING OR TWISTING FLAT STRIPS OF MATERIAL.

1,379,981.

Specification of Letters Patent. Patented May 31, 1921.

Application filed June 10, 1919. Serial No. 303,120.

To all whom it may concern:

Be it known that I, JOHN SWANZY HARLEY, a subject of the King of Great Britain and Ireland, and residing at "The Laurels", 5 Waltham Abbey, in the county of Essex, England, have invented certain new and useful Improvements in or Relating to the Production of Yarn, Twine, Cord, and the like by Spinning or Twisting Flat Strips 10 of Material, of which the following is a specification.

This invention relates to the production of yarn, twine, cord and the like by spinning or twisting flat strips of material as, 15 for instance, paper.

According to the invention the flat strip of material is drawn from a reel or bobbin of the material, which reel or bobbin is rotated about an axis at right angles to the 20 axis about which the reel or bobbin is caused to rotate by drawing off the strip material either directly through a die of such diameter that the spun product is frictionally gripped by the die or first through a guide 25 which may be in the form of a tube.

The die which ordinarily is of somewhat less diameter than the spun product may be rotated and is arranged at a suitable distance from the bobbin.

30 As exemplifying the sizes of dies which may be employed in accordance with the invention, in spinning paper strip the following particulars are given:

Internal diameter of die.	Paper.		
	Weight per ream of 380 sheets double crown (20" x 30").	Thickness.	Width.
0.040 inch.	19 lb.	0.003 inch.	1/2 inch.
0.055 "	"	"	1/2 "
0.062 "	"	"	1 1/2 "
0.088 "	"	"	2 1/2 "

45 A machine in accordance with the invention will comprise essentially a spinning head adapted to rotate the bobbin, a die held in suitable relationship with the spinning head and means for drawing the strip 50 material from the bobbin (by the relative rotation between which and the die for the material is spun) directly through the die or through a guide which may be in the form of a tube.

55 A machine in accordance with the inven-

tion may comprise a head secured on a hollow spindle rotatably mounted in suitable bearings, and provided with means for supporting a bobbin or reel of the strip material in such manner that the strip material as it is drawn off its bobbin or reel passes through the hollow spindle, for which purpose the axis about which the bobbin or reel rotates as the strip is drawn off, may be arranged at right angles to the axis of 60 rotation of the hollow spindle, which acts as a guide to the paper strip a die in advance of the hollow spindle and means for drawing the strip material successively through the hollow spindle acting as a 65 guide and the die.

The hollow spindle acting as a guide for the paper strip as it is drawn off the bobbin or reel, in one form of construction, is provided with a bell mouth serving to direct 75 the strip material to a constriction within the spindle, the succeeding portion of the hollow spindle being of greater diameter.

In advance of the hollow spindle, a die of somewhat less diameter than the finished 80 cord may be arranged.

As illustrating the proportions which it has been found that the parts referred to may have, the following particulars are given:

In spinning a single strip of paper of 96 mm. in width or two strips of 48 mm. in width, the die or constricted portion of the spindle may be three eighths of an inch in diameter and one half an inch in length. 90

The second die may have a diameter of 0.170 inches and the distance between the constriction and the die may be two feet.

Certain constructions in accordance with the invention are illustrated by way of example in the accompanying drawings in which:

Figure 1 is a side elevation of a machine partly in section.

Fig. 2 is a diagrammatic plan view of a 100 frame provided with spindles on each side.

Fig. 3 is a front elevation partly in section of a portion of the machine.

Figs. 4, 5 and 6 are views on a larger scale illustrating a means for securing the 105 bobbin or reel in association with the spindle.

In the drawings, 1 is the reel or bobbin, 2 the strip material thereon, 3 the carrier for the bobbin or reel, 4 the spindle which in 110

the constructions illustrated by Figs. 1 to 6 is fixed to the carrier 3, is hollow and is provided with a constriction 5 and a bell mouth 6. 7 is the bearing for the spindle, 8 a sprocket adapted to rotate the spindle by means of a chain from the sprocket 9, 10 is a die secured in the carrier 11, 12 is a purchase drum, 13 a pulley over which the cord passes, 14 a traversing device adapted to lay up the yarn, twine or cord in a suitable manner on the bobbin 15, which is pressed by the arm 16 pivoted at 17 against the rotating drum 18.

In the operation of the machine as illustrated in Figs. 1-6, the strip material is drawn from the bobbin 1 through the hollow spindle 4 which is maintained in rotation by means of the sprockets 8 and 9 and the chain coöperating therewith to the die 10, the relative rotation of the bobbin 1 and the die 10, which is effected in this way, will cause the strip material to be spun or twisted, the purchase drum 12 about which the strip material is wound one or more times, operating to draw the material off the bobbin and through the die. From the purchase drum the spun material passes over the pulley 13 and the traversing device 14 on to the bobbin 15 which being pressed 30 by the arm 16 against the rotating drum 18 is driven by friction therefrom.

The die 10, it may be mentioned, performs a double function, in that it arrests the twist or spin and also serves to standardize, smooth or perfect the cord, twine or 35 yarn produced.

A suitable method of mounting the reel or bobbin of paper in the carrier is shown in Figs. 4, 5 and 6, in which 1^a is a spindle on which the bobbin 1 is rotatably mounted, 40 the spindle being provided with squared ends 1^b by which it is secured in the eyes 3^a of the carrier 3.

Having now described my invention, what I claim as new and desire to secure by Letters Patent is:—

An apparatus for the production of yarn, twine, cord and the like comprising a bearing, a tubular member rotatably mounted in said bearing and provided with legs, a shaft 50 carried by said legs and arranged perpendicularly to the axis of the tubular member, a bobbin carrying strip material mounted on said shaft, the interior of said tubular member having a restricted opening which 55 merges into a bell mouth, through which the strip material is drawn from said bobbin, means for rotating said tubular member, means for drawing the strip material through said tubular member while said 60 tubular member is rotating, and a die provided with an opening having a diameter approximately equal to the thickness of the cord to be formed, located between the tubular member and the last named means and 65 designed to arrest the rotation of the strip and to compress the cord formed from the strip material.

In testimony whereof I have signed my name to this specification.

JOHN SWANZY HARLEY.
